Application filed January 7, 1895. Serial No. 534,135. Term of patent 7 years.

To all whom it may concern:

Be it known that I, EDWARD R. IVES, a citizen of the United States, residing at Bridgeport, in the county of Fairfield and State of Connecticut, have invented and produced a new and original Design for Toy Passenger-Cars; and I do declare the following to be a full, clear, and exact description of the same, reference being had to the accompanying drawings, forming a part thereof.

The leading feature of my design consists in the representation of a passenger car having a body, wheels, openings or windows, &c., and at the windows representations of passengers.

In the drawings, Figure 1 is a side view of my newly-designed toy car, and Fig. 2 is a cross-section thereof.

1 denotes the body of the car; 2, the wheels; 3, the openings representing windows, and 4 ²⁰ the representations of passengers at the windows, these representations of passengers being flat relief figures within the sides of the car body, as shown in Fig. 2, and being close to the openings or windows.

What I claim is—

The design for a toy passenger car, substantially as shown and described.

In testimony whereof I affix my signature in presence of two witnesses.
